UNITED STATES PATENT OFFICE.

THEODORE C. KRINGS, OF YORKTOWN, IOWA.

DISINFECTANT-DISTRIBUTER.

1,208,985.

Specification of Letters Patent. Patented Dec. 19, 1916.

Application filed April 27, 1916. Serial No. 93,909.

To all whom it may concern:

Be it known that I, THEODORE C. KRINGS, a citizen of the United States, residing at Yorktown, in the county of Page and State 5 of Iowa, have invented certain new and useful Improvements in Disinfectant-Distributors; and I do declare the following to be a full, clear, and exact description of the invention, such as will enable others skilled 10 in the art to which it appertains to make and use the same.

This invention relates to certain new and useful improvements in disinfectant distributors or sprayers for animals.

15 The object of the invention is to provide a member adapted to be rubbed against by animals affected with parasites, and when so rubbed against, to automatically permit a quantity of the fluid contained in a tank to 20 be sprayed over the animal, said fluid being of such a nature that it will tend to destroy the parasites.

A further object of the invention is to provide a spraying device of this character in 25 which the fluid will be sprayed in measured quantities, to thereby avoid wasting of the fluid.

An additional object of the invention is to 30 provide a device of this character which will be simple, strong, durable and inexpensive in construction efficient and reliable in operation, and well adapted to the purpose for which it is designed.

With these and other objects in view, the 35 invention consists of certain novel features of construction, and the combination and arrangement of parts as will be hereinafter fully described and claimed.

In the accompanying drawings, in which 40 similar reference characters designate like parts throughout the several views, Figure 1 is a side elevation of a device constructed in accordance with this invention; Fig. 2 is a front elevation of the same; Fig. 3 is a central vertical sectional view taken on the plane of the line 3—3 of Fig. 2 showing the slide valve in closed position; Fig. 4 is a similar view showing the slide valve in open position; Fig. 5 is a transverse sectional view taken on the plane of the line 5—5 of Fig. 1; Fig. 6 is a similar view taken on the plane of the line 6—6 of Fig. 1; and Fig. 7 is a similar view taken on the plane of the line 7—7 of Fig. 1.

55 Referring more particularly to the drawings the reference numeral 1 designates an

upright standard, formed preferably of a channel iron bar, and having connection at its lower end in any suitable manner, to a horizontal rubbing member 2, the latter being spaced a short distance from the ground or other surface on which the device is supported by an upright leg member 3. The rubbing member 2, leg member 3, and lower end of the standard 1 form in effect the base 60 of the device. As shown, the rubbing member 2 is provided on its upper face with a pair of longitudinally extending grooves 3', the purpose of which will be hereinafter described.

Secured at its intermediate portion as at 4 to the upper end of the standard 1, is a substantially rectangular-shaped frame 5, composed of a U-shaped bracket 5, the outer free ends of the arms of which are turned 75 inwardly as at 6. This frame 5 surrounds a substantially rectangular-shaped disinfectant tank 7 which is preferably slidable therein, so that the tank may be readily and easily removed therefrom for filling or the like. Secured in a similar manner to the standard 1 and disposed in a plane below the bracket 5, is a U-shaped member 8, the arms 9 of which form guide members for the upper end of a slightly movable rubbing member to 80 be hereinafter described. As shown the bottom of the tank 7 rests upon the upper edges of the arms 9. The upper side of the tank is here shown provided with a filling opening 10, while connected to the bottom of the 85 same is a substantially horizontal valve casting 11. This casting 11 is closed at its forward end, but communicates with the interior of the tank 7 by an inlet 11', while its rear end is open, thereby providing an outlet 90 opening to allow the contents of the tank to flow from the same.

Pivottally mounted at 12 at its lower end to the upper side of the horizontal rubbing member 2, at a point in substantially vertical alinement with the outlet end of the casting 11, is a movable rubbing member 13. This member 13 is slightly inclined rearwardly and is so positioned below the outlet end of the casting 11 as to allow the disinfectant to flow onto and run down the same when said outlet is opened, in a manner to be described. A recess 14 is arranged in the rear side of the member 13 to receive one end of a coiled spring 15, which, as will 105 be readily understood, holds said member normally in its forwardmost position. The

front or rubbing side of the member 13 is provided with suitable elements or means for causing the disinfectant to travel in a tortuous path down the same, said means comprising a series of grooves or channels 16, which are inclined downwardly, the adjacent ones extending in substantially opposite directions from the opposite edges of the member, and having their lower ends 10 terminating a short distance from the adjacent ends of the latter, whereby the disinfectant will flow from one groove to the other and ultimately reach the horizontal rubbing member 2 and be confined in the 15 grooves 3 therein. It is to be understood that ribs or other similar elements may be substituted for the grooves 16, as may be desired.

Secured to the upper end of the member 13 in any suitable manner, is a plate 17 having a notch 18 in its upper edge and this notch 18 is adapted to engage the notched out portion 19 of the rear end of a substantially cone-shaped plug 20, which is normally seated in the rear or outlet end of the cylinder 11. The forward inner end of the plug 20 extends into the interior of the casing 11, and is provided with a plunger or piston head 21. This head 21 is disposed 25 forwardly of the inlet 11' of the casing 11 when the rubbing member 13 is in its normally forwardmost position, but when said member is moved rearwardly, the head 21 will be moved across and beyond 30 said inlet 11', thereby cutting off the flow of the contents of the tank 7 into the casing 11 and forcing the disinfectant in the latter rearwardly. Simultaneously with the actuation of the valve at the forward end of 35 the casing 11, the tapered or cone shaped portion of the plug 20 will be moved into the outlet opening in the rear end of the casing 11 to allow the fluid to flow or fall upon the member 13, from which it is applied to 40 the bodies of the animals. This arrangement provides in effect a double slide valve for allowing the disinfectant to be dispensed in measured quantities, thereby preventing extravagant waste of the same. 45 The fluid so dispensed when the member 13 is rubbed or pressed against by the animals, such as hogs, falls directly upon the mem-

ber 13, some of it running tortuously down the same as heretofore described, while the remainder of it splashes upon and is applied by said rubbing to the bodies of the animals. 55

From the foregoing description, taken in connection with the accompanying drawings, the operation and construction of the invention will be readily understood without a more extended explanation. 60

As various changes in form, proportion and the minor details of construction may be resorted to without departing from the spirit of the invention, I do not wish to be limited to the construction herein shown and described other than that set forth in the appended claim. 65

I claim: 70

A device of the class described comprising a base, a standard rising from said base at the rear end thereof, a U-shaped member secured at its intermediate portion to said standard near the upper end thereof, 75 the arms of said member extending horizontally forwardly of said standard to provide a pair of spaced guide members, a substantially rectangular-shaped frame arranged in a plane above said member and secured 80 to said standard at one of its ends and extending horizontally forwardly of the same, a rectangular-shaped tank slidably received in said frame and resting upon said guide members, a horizontal valve casing fixed at 85 its forward end to the forward end of said tank and communicating with the interior of the same, the rear end of said casing being disposed between said guide members, a slide valve arranged within said casing, a 90 substantially upright rubbing member pivoted at its lower end to said base and having its upper end slidably received between said guide members and operatively connected to said valve, and means for normally holding 95 said rubbing member in its forwardmost position and said valve in its closed position.

In testimony whereof I have hereunto set my hand in presence of two subscribing witnesses.

THEODORE C. KRINGS.
